SEWING CABINET

Filed Aug. 4, 1928

FIG. 1

FIG. 2

INVENTOR.

VICTOR E. CARLSON

BY

A.B. BOWMAN

ATTORNEY

UNITED STATES PATENT OFFICE

VICTOR E. CARLSON, OF SAN DIEGO, CALIFORNIA

SEWING CABINET

Application filed August 4, 1928. Serial No. 297,571.

My invention relates to sewing cabinets and the objects of my invention are: First, to provide a device of this class which combines all the receptacles for equipment necessary for sewing, darning, mending, or the like in a single combination article of furniture; second, to provide a device of this class which may be easily moved from place to place; third, to provide a device of this class which collapses or folds up when not in use, thereby greatly reducing the floor space necessary for storage when not in use; fourth, to provide a device of this class in which the various articles needed for mending, sewing, or the like, are all readily accessible; fifth, to provide a device of this class which has a large boxlike container in connection therewith for holding any articles to be mended and forming a storage space therefor until such time as they can be attended to; sixth, to provide a device of this class which may be easily cleaned or dusted when it is collapsed or closed; and seventh, to provide a device of this class which is simple of construction, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a perspective view of my sewing cabinet, showing it in open position; and Fig. 2 is a side elevational view thereof showing my sewing cabinet in closed position.

Similar characters of reference refer to similar parts and portions throughout the several views of the drawings.

The support members 1, casters 2, brace 3, tray 4, tray compartments 5, receptacle 6, receptacle lid 7, shelf support 8, shelves 9, and chains 10, constitute the principal parts and portions of my sewing cabinet.

The two support members 1 are provided,

one at either side of my sewing cabinet. The support members 1 are substantially triangular in shape with their apexes towards the top. The lower or base portion 1^a is broadened and is mounted on the casters 2. The upper portion 1^b is hollowed out so as to reduce the weight of the supports. The upper extremities of the supports 1 are joined together by a horizontal brace 3. Just below the cut out portion 1^c of the supports 1 and extending between said supports is mounted a shallow tray 4 having several tray compartments 5 positioned therein, as shown in Fig. 1 of the drawings. The one side of the tray extends approximately flush or in line with the lower base portion 1^a of the supports 1 and has hinged to this side a receptacle 6 which is deep enough to rest on the floor when the upper edge thereof is even with the upper edge of the tray, as shown in Fig. 1. The receptacle is provided with a lid 7 which fits flush with the top thereof and is hinged to the extended side of said receptacle. The lid when positioned over the top of the receptacle forms a small work table or shelf. Suitable stop members 6^a prevent the lid 7 from telescoping within the receptacle 6.

The other side of the tray 4 does not extend as far as the first side and has hinged to its lower edge a shelf support 8 which is in the shape of a rectangular box. The bottom portion of the shelf support is approximately flush with the edge of the base portion 1^a of the support 1, as shown in Fig. 2. Positioned in the shelf support are a plurality of shelves 9 each of which has a low wall 9^a along its outer edge. The movement of the shelf support 8 is limited relative to the tray 4 by means of chains 10 which are each secured by one end to a support member 1 and by the other end to an upper portion of the shelf support, as is shown in the drawing. When desiring to close my sewing cabinet, the lid 7 is placed over the receptacle 6. The receptacle 6 is then turned on its hinges until it rests bottom side up on the tray 4. The shelf support 8 is then moved to a vertical position bringing its inner edge against the side of the receptacle 6. A suitable hook or eye portion 6^b is secured to the corners of the receptacle 104

6 which are adjacent to the upper inner side portions of the shelf support 8 when closed, as shown in Fig. 2. When the receptacle and shelf support are secured together, they hold the sewing cabinet in its closed position.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In a sewing cabinet, a pair of supports, a horizontally positioned tray supported thereby, said tray extending further to one side of said supports than to the other, a shelf support having an open side hinged to the lower edge of said tray on the lesser extended side thereof, a deep receptacle hinged to the upper edge of said tray on the greater extended side thereof, said receptacle adapted, when closed, to be positioned bottom side up upon said tray and presenting a side surface in a plane common with said lower edge of the tray and means for securing said shelf support with its open side contiguous with said side surface of said receptacle.

2. In a sewing cabinet, a pair of supports, a horizontally positioned tray supported thereby, said tray extending further to one side of said support than to the other side thereof, a deep receptacle hinged to the further extended side of said tray along its upper edge, the depth of said tray being substantially equal to the height of said upper edge above the base of said supports, a shelf support hinged in a horizontal line at the other side of said tray and shelves mounted in said shelf support, said receptacle adapted to swing on said hinges in a position over said tray when not in use, and into a position with its bottom side in the plane of the base of said support when in use, said shelf support adapted to be held in a substantially vertical position against the one side of said receptacle when not in use and at an angular position when in use.

In testimony whereof, I have hereunto set my hand at San Diego this 27th day of July, 1928.

VICTOR E. CARLSON.
